UNITED STATES PATENT OFFICE

134,575

DESIGN FOR AN EMBLEM PIN

L Lee Pandres, Dallas, Tex.

Application March 23, 1942, Serial No. 106,278

Term of patent 3½ years

To all whom it may concern:

Be it known that I, L Lee Pandres, a citizen of the United States, residing at Dallas, in the county of Dallas and State of Texas, have invented a new, original, and ornamental Design for Emblem Pins, of which the following is a specification, reference being had to the accompanying drawing, forming a part thereof.

Fig. 2 is a side edge view of said emblem pin.
The drawing is lined to indicate contrasting colors.

I claim:
The ornamental design for an emblem pin, as shown and described.

L LEE PANDRES.
